CONTAINER CLOSING APPARATUS

Olav Bjering and John Hohl, Toledo, Ohio, assignors to
Owens-Illinois Glass Company, a corporation of Ohio

Filed May 15, 1958, Ser. No. 735,532

4 Claims. (Cl. 53—314)

The present invention relates to closing apparatus for bottles and jars and particularly to means for affixing screw-threaded closure caps to product-filled open-top containers while they move continuously along a horizontal path.

An object of our invention is the provision of novel means for threading closure caps upon bottles and jars in such fashion that they will effectively seal the containers, yet can be removed by the ultimate consumer without the difficulties so often attendant opening of jars having screw-threaded closure caps.

Another object of our invention is the provision of simple and effective means for threading closure caps upon bottles and jars in which such means comprises closure cap spinning rolls for engaging the threaded attaching skirt of the closure caps and novel means for regulably controlling the skirt gripping pressure of the rolls whereby to predetermine to a satisfactory degree the tightness of the applied caps.

A further object of our invention is the provision of novel means for adjusting the elevation of the operating position of the spinning rolls as required by variations in the height of the containers being capped or closed. Thus the rolls can be set accurately for most effective contact with the closure cap skirt.

It is also an object of our invention to provide novel means for adjusting the operating position of the closure cap spinning rolls and the means for transmitting power to the spinning rolls.

Other objects will be in part apparent and in part pointed out hereinafter.

In the drawings:

Fig. 1 is a front elevational view of a closure cap applying machine incorporating our invention.

Fig. 2 is a top plan view.

Fig. 3 is a transverse sectional elevational view taken substantially along the line 3—3 of Fig. 1.

Fig. 4 is a fragmentary detail sectional elevational view of the means for adjusting the angular position of the spinning rolls.

Fig. 5 is a sectional elevational view taken substantially along the line 5—5 of Fig. 1.

Fig. 6 is a view schematically showing the spinning rolls adjustment.

Fig. 7 is a plan view schematically showing two possible operating positions of the spinning rolls intended to vary the closure cap gripping effectiveness.

The illustrated embodiment of our invention is shown in operating relationship to a horizontal continuously moving conveyor 15 upon which jars 16 or the like product-filled containers travel through the closure cap receiving and applying zones 17 and 18, respectively (Fig. 1). The jars have exteriorly screw-threaded necks 19 which are designed to accommodate screw-threaded closure caps 20 such caps being picked from the discharge end of an inclined cap chute 21 one at a time by the jars as they move past the chute. These closure caps quickly drop over the jar necks and are momentarily supported

2

in partially telescoped relationship thereto by a leveling device 22 (Fig. 3) the latter being in the zone 18 and specifically that occupied by what we term the pair of primary closure cap spinning rolls 23. The foregoing mechanism is disclosed and forms part of the subject matter claimed in a co-pending allowed application of S. L. Harmon and John Hohl, Serial Number 653,955 filed April 19, 1957, now U.S. Patent No. 2,855,736, titled "Method of and Apparatus for Closing Bottles and Jars," 10 assigned to the assignee of the present application.

Briefly the apparatus is a self-contained unit capable of placement in an operating position relative to a packer's conveyor line and incorporating means whereby it may easily be adjusted to the conveyor height and width, 15 as well as to handle bottles or jars varying height and/or diameter. The apparatus incorporates closure cap spinning rolls which at least partially thread closure caps upon the containers thereby lowering the caps to a level at which they may be engaged by secondary or tightening rolls. These rolls are carried by means through which adjustments as required by jar or bottle height and diameter variations may be effected. Also the rolls are angularly adjustable and thereby provide for a so-called "fine adjustment" of the pressure of the rolls upon 20 the closure caps. Further the apparatus includes means for effectively holding the containers against rotation as they travel along the conveyor and additionally secure them in normal upright positions to receive closure caps.

Specifically the apparatus comprises a horizontally 25 elongated main frame 25 positioned in part alongside the conveyor 15 (Figs. 1 and 2) and provided exteriorly of the side wall 26 facing the conveyor with a vertical slide 27 on which a slideway 28 carried by a sub-frame 29 is adjustable vertically. This sub-frame 29 includes a bar 30 which is suitably connected to adjusting means including a hand-wheel 31 for changing the elevation of this frame as conditions require. Two longitudinally spaced supports in the form of horizontal rods 32 are carried by the bar 30 and extend across the conveyor 15 35 for supporting a pair of horizontal platforms 33 which in turn carry the aforementioned closure cap spinning rolls 23 and others as will be apparent presently. These platforms 33 are elongated in the direction of the length of the conveyor 15 and near their ends are provided with 40 sleeves 34 which are telescoped over and slidable along the rods 32. Thus, the platforms 33 are capable of being moved horizontally to thereby vary the transverse spacing of the closure cap spinning rolls 23 as may be required by the specific diameter of the closure caps being applied.

The mechanism for moving the platforms toward and away from each other may comprise adjusting rods 35 individual to and disposed immediately beneath and parallel to the sub-frame supporting rods 32. Each such 45 rod 35, intermediate its ends, is journaled in a bearing 36 on the lower side of a center bar 37 being locked therein against axial movement by retaining devices 38. Each end portion of the adjusting rod 35 is threaded through a peripherally channelled collar 39 which has 50 separable connection with a flange 40 depending from one of the sleeves 34. A retaining block 41 secured in place by screws 42 holds the collar 39 in assembled relationship to the sleeve 34. One end of each rod 35 has a square extension 35a to accommodate a turning implement (not shown) of some sort while the other end of each rod carries a sprocket wheel 43. These sprocket wheels are connected together by a sprocket chain 44 so that with rotation of either rod both will be actuated and thereby effect corresponding adjustment of both ends of 55 the platforms 33. Such adjustment, as stated heretofore, changes the spacing between the spinning rolls 23. 60

In addition to the pair of primary spinning rolls 23,

we have shown two pairs of secondary or tightening rolls 23^a and 23^b which are spaced longitudinally from the primary rolls 23. These secondary rolls normally operate at a slightly lower elevation than the primary rolls for the reason that the closure caps will have been moved downwardly on the containers by the threading action of the primary rolls to a level requiring the illustrated positioning of the secondary rolls (see Fig. 1). Since the mountings for the primary rolls 23 are identical structurally, we will specifically describe only one of them. At that end of each platform 33 (Fig. 4) nearest the cap chute 21 is a horizontal arm 45 formed with a vertical opening 46 therethrough. Spaced laterally inwardly from this arm 45 (Fig. 2) is a bearing 47 for a horizontal hinge pin 48 (Figs. 3 and 6) upon which a spinning roll carrier 49 is mounted. This carrier (Fig. 5) includes a depending tubular housing 50, a concentric internal sleeve 51 having each of its ends abutting the inner ring of a ball bearing 52 and an axially recessed shaft section 53 which extends upwardly through the carrier where it is connected to a driven pulley or sheave 54. This shaft section 53 is journaled in said bearings 52 and at its upper end is secured in a thrust bearing 55 which holds it against axial movement. At the lower end of this shaft section is a split lock collar 56. Through the lock collar and into the axial recess 57 in said shaft section a portion of a lower shaft section 58 extends, the upper end of the latter being threaded into said recess whereby to provide for adjustment of the lower section axially relative to the upper section 53. Thus the operating elevation of the closure cap spinning roll 23 may be varied as conditions require. The lock collar 56 functions in the customary manner to secure the lower shaft section against undesired rotation relative to the other section 53. In addition to the described axial adjustment of the roll supporting shaft the angular position of the roll may be varied.

Such variation in the roll position is obtainable by means including a pair of rods mounted in the carrier. One rod 59 is threaded vertically through the carrier 49 and has its lower end contacting the arm 45 or a hardened block 60 thereon. By adjusting this rod axially the cap spinning roll may be moved for example in the fashion indicated in Fig. 6. This rod serves as a stop for limiting inward movement of the rolls toward each other. Thus we provide fine control of the operating positions of the rolls 23. The second rod 61 is threaded vertically in the carrier 49 and extends downwardly through an opening 62 in the arm 45. Below this arm the rod carries a coil spring 63 which is confined between a head 61^a on the rod and a collar 61^b. By rotating this spring carrying rod 61 the tension of the spring may be adjusted and the cap skirt gripping pressure of the rolls regulably controlled.

The mounting of the secondary or tightening rolls 23^a and 23^b is substantially identical with that described in connection with the primary rolls 23, the only exception being that the housings 50 extend through vertical openings 50^a provided in the platforms 33.

Rotation of the pulleys 54 or sheaves at the upper ends of the roll carrying shafts (Figs. 1 and 2) is obtained by means of an endless belt 54^a trained over said pulleys and idler pulleys 64, the latter being carried by horizontal adjustable slides 65. A pulley 54^b is connected to a gear box 54^c, a shaft 54^d, and power transmitting means 54^e to a motor M. Automatic tensioning means 66 (Fig. 2) for the drive belt comprises a horizontal bell-crank lever 67 having a belt engaging pulley 68 at one end and a spring device 69 at the other end which constantly yieldingly holds the pulley 68 in contact with the belt. It is apparent that with adjustment of the spacing between the platforms 33 the slides 65 will be moved and the angle between the arms of the bell-crank lever 67 may require re-setting to obtain the desired tension in the belt 54^a.

It is important that the bottles or jars 16 be held against tipping and rotation in order to insure both delivery of closure caps thereto and later threading of the caps onto the containers. To this end, we provide a pair of continuously traveling endless belts 70 one on each side of the conveyor 15. These belts are of substantial height (Fig. 5) to insure effective gripping of the jars at diametrically opposed points. Obviously these belts move in the same direction and at the same speed as the conveyor 15. They are mounted upon supporting frames 71 which are adjustable relative to each other in a direction transverse to the length of the conveyor to accommodate containers of different diameter. Such adjustment is obtained by suspending the frames from a pair of horizontal supporting rods 72. Sleeves 73 at the upper end of hangers 74 are slidably positioned upon the rods 73. These sleeves are connected to threaded adjusting screw-rods 75 which are journaled in bearings 76 and held against axial movement therein by collars 77. Arms 78 on the sleeves have the rods threaded therethrough. Sprockets 79 at one end of the rods are connected together by a sprocket chain 80. Thus rotation of either screw-rod 75 will serve to adjust the steadyng or gripping belt carrying frames relative to each other as may be required by the ware being handled.

Although the mode of operation is deemed obvious and perhaps adequately described in the foregoing, it briefly comprises placement of product-filled containers in upright position on the conveyor 15 in advance of the cap chute 21. These containers move in succession beneath and remove threaded closure caps from the chute, such caps at this time dropping by gravity and thereby becoming partially telescoped over the screw-threaded necks of the bottles or jars. The leveler 22 temporarily supports the closure caps 20 spaced a short distance above the top end of the jars while the primary closure cap spinning rolls 23 grip the cap skirt and impart rotary motion to the cap. As this occurs the leveler 22 moves downwardly permitting actual partial or complete threading of the cap onto the container. The container with the closure cap at least partially threaded thereon then moves on to the secondary rolls 23^a and 23^b, which, if the cap is insufficiently threaded onto the jar, completes the operation.

The jar gripping means, as stated, may be adjusted to accommodate containers of different diameter. The platforms which carry the several spinning rolls are adjustable to change the spacing between the rolls as may be needed to apply closure caps of different diameter. Adjustment of the roll carriers 49 relative to the arms 45 therebeneath also changes the angular position and transverse spacing of the spinning rolls. Axial adjustment of the shaft section 58 which is directly connected to the rolls serves to regulably control the operating elevation of the rolls as is needed when the jars vary in height.

Modifications may be resorted to within the spirit and scope of the appended claims.

We claim:

1. In container closing apparatus, a horizontal continuously moving conveyor for carrying product-filled containers having exteriorly threaded necks through adjacent closure cap receiving and applying zones, closure delivery means in the receiving zone operable to only partially telescope screw-threaded closure caps over the threaded necks, means for rotating the telescoped closure caps to thereby completely thread them upon the container necks, comprising, a pair of yieldable resilient closure cap spinning rolls positioned one at each side of the path of travel of the containers, said spinning rolls having their axes normally substantially parallel and extending generally vertically, a pair of shafts coaxial with and supporting the spinning rolls, said shafts aligned with each other in a direction transverse to the length of the conveyor, a horizontally movable slide supporting

each shaft and a spinning roll, a horizontal rod upon which the slides are movable axially to vary the spinning roll spacing, means for moving the slides and rolls horizontally toward and away from each other, a horizontal arm projecting from each movable slide beneath the corresponding bearing carrier, a screw-threaded rod extending vertically through the arm and carrier near the free end of the latter, said rod threaded in the carrier and freely movable axially through the arm, yielding means on the rod below said arm for urging arm and carrier together, and an adjustable stop for limiting relative movement of the arm anterior in one direction.

2. In container closing apparatus, a pair of closure cap spinning rolls spaced apart horizontally with one at each side of a horizontal path along which product-filled jars having exteriorly screw-threaded necks and screw-threaded closure caps partially telescoped thereover move continuously, said spinning rolls rotatable about vertical generally parallel axes for gripping the closure caps and threading them upon the jar necks, a supporting shaft for each roll extending upwardly therefrom, a pivoted carrier for each shaft with the pivot extending horizontally substantially parallel to said path, an arm to which one end of the carrier is pivoted and yielding means urging the arm and carrier together comprising, a screw-threaded rod threaded through the carrier and freely slideable through the arm, spring means on the rod and that side of the arm remote from the carrier, means for adjusting the rod axially to vary the spring tension and the pressure of the rolls upon the closure caps and adjustable stop means for predetermining the intermost positions of the rolls.

3. In container closing apparatus, a pair of closure cap spinning rolls spaced apart horizontally with one at each side of a horizontal path along which product-filled jars having exteriorly screw-threaded necks and screw-

threaded caps partially telescoped thereover move continuously, said spinning rolls being rotatable about vertical generally parallel axes for gripping the closure caps and threading them on the jar necks, a supporting shaft for each roll extending upwardly therefrom, a pivoted carrier for each shaft with the pivot thereof extending horizontally substantially parallel to said path, means providing for axial movement of said shaft in its carrier to thereby adjust the operating level of the corresponding closure cap spinning roll and releaseable means for locking the shaft in any axially adjusted position.

4. In container closing apparatus, a pair of closure cap spinning rolls spaced apart horizontally with one at each side of a horizontal path along which product-filled jars having exteriorly screw-threaded necks and screw-threaded closure caps partially telescoped thereover move continuously, said spinning rolls being rotatable about vertical generally parallel axes for gripping the closure caps and threading them upon the jar necks, a supporting shaft for each roll extending upwardly therefrom, a pivoted carrier for each shaft with the pivot extending horizontally substantially parallel to said path, a rotatable sleeve extending vertically in each carrier, each said shaft being threaded axially into the sleeve whereby rotation of the shaft relative to the sleeve adjusts the operating level of the corresponding closure cap spinning roll and releasable lock means for securing the shaft against independent bodily movement relative to the sleeve.
